UNITED STATES PATENT OFFICE.

ERNEST ALSCHULER, OF ST. LOUIS, MISSOURI, ASSIGNOR, BY MESNE ASSIGNMENTS,
TO NATIONAL CARBON COMPANY INC., OF CLEVELAND, OHIO, A CORPORATION
OF NEW YORK.

SWITCH.

1,389,088.

Specification of Letters Patent. Patented Aug. 30, 1921.

Application filed June 9, 1917, Serial No. 173,689. Renewed January 22, 1921. Serial No. 439,319.

To all whom it may concern:

Be it known that I, ERNEST ALSCHULER, a citizen of the United States, residing at St. Louis, in the county of St. Louis, State of Missouri, have invented certain new and useful Improvements in Switches; and I do hereby declare the following to be a full, clear, and exact description of the invention, such as will enable others skilled in the art 10 to which it appertains to make and use the same.

This invention relates to switches for electric circuits and more particularly to switches adapted for use on battery hand 15 lamps.

It is an object of the invention to produce a device of simple construction and reliable operation which may be manipulated by hand to cause the intermittent lighting of 20 the lamp as desired, or in case it is desired that the lamp be retained in lighted condition independently of hand manipulation, means are provided for maintaining the lamp circuit in closed condition.

25 In the preferred embodiment of the invention a push button is used to manipulate a contact element when intermittent lighting of the lamp is desired. To retain the lamp in lighted condition a sliding thumb- 30 piece operating a second contact element which is separate from and wholly independent from the first contact element is provided.

The construction of the device will be apparent from the following description of 35 one embodiment thereof taken in connection with the accompanying drawings, of which—

Figure 1 is a view of a battery hand lamp 40 showing the casing and switch in section; Fig. 2 is an enlarged sectional view of the mechanism of the switch; Fig. 3 is a view in section along the line 3—3 of Fig. 2; Fig. 4 is an enlarged detail view of the slide for 45 manipulating one of the contact fingers; Fig. 5 is an enlarged detail view of one of the contact fingers; Fig. 6 is a similar view of the other contact finger; Fig. 7 is a view similar to Fig. 1 showing a modified form of 50 switch; Fig. 8 is an enlarged sectional view of the modified form of switch; Fig. 9 is a view in section along the line 9—9 of Fig. 8;

and Fig. 10 is a perspective view of the contact elements of the switch.

Referring to the drawings, in which similar reference characters denote similar parts throughout the several views thereof, 10 represents a metallic case of any form of battery hand lamp to which it is desired to apply the invention. One end of the case is 55 formed as a cover 11 which may be opened to permit a battery to be removed or replaced. The other end of the casing has a pocket 12 which serves as a reflector and also 60 protects the lamp 13 which is set into a screw-threaded socket portion 14 at the base of the pocket. The battery 15 is provided with a spring finger terminal 16 adapted to engage one terminal of the lamp. The other 65 terminal 17 of the battery is formed as a 70 spring contact finger lying adjacent to but normally out of contact with the members of the switch.

The switch itself comprises a pair of 75 spring contact elements 18 and 19 attached to the casing 10 by a common rivet 20. Element 18 is bent inwardly at its free end and provided with a button 21 extending through an aperture in the side of the casing and by which the element may be manipulated by 80 hand. The other element 19 is somewhat shorter than element 18 but is provided with a similar inwardly bent portion at its free end. The central portion of element 19 is bent up as at 22 to form a cam face. An 85 aperture 23 is cut through element 18 to permit the cam face to extend through the latter element and a corresponding aperture is provided in the casing.

For the purpose of manipulating the contact element 19 a sliding member 24 is 90 mounted upon the outside of the casing. This sliding member comprises flat end portions provided with a suitable curvature corresponding to that of the casing. Between 95 the end portions is a raised central portion which forms a chamber or recess occupied by the cam face portion of element 19. Sliding member 24 is provided with two tangs 100 extending outwardly and adapted to project through slots in the casing at the sides of the cam member. These tangs are so proportioned that with the curved end portions of the sliding member they will retain the

latter in place upon the casing and yet permit a sliding movement of the same lengthwise of the casing.

When the members of the switch occupy the position shown in the drawings the lamp circuit will be open as both of the elements are out of contact with terminal 17 of the battery. If it is desired to light the lamp directly under the control of the thumb or fingers of the user the button 21 is depressed to bring the element 18 against battery terminal 17. At the same time element 19 will also be depressed since it lies under element 18, but this will merely furnish an additional contact. The circuit of the lamp passes from the terminal 17 through the switch elements 18 and 19, casing 10, lamp socket 14, the lamp 13 and its other terminal back through contact 16 to the other terminal of the battery. As long as button 21 is held depressed the lamp will be illuminated.

If it is desired that the lamp should burn continually without the necessity of holding button 21 in depressed position, slide 24 is pushed along the casing and by its cam action upon the portion 22 of contact element 19 will cause the latter to be depressed to engage battery terminal 17. Contact element 18 will under this condition of operation remain in its normal position, but circuit will be established through element 19 to the casing and thence through the lamp as traced above.

In the modification shown in Figs. 7 to 10 the contact elements are formed from a single piece of metal which is cut as shown most clearly in Fig. 10 to form the contact element 18' and the contact element 19' which consists of two parts on opposite sides of the element 18'. Both parts of element 19' are bent up as shown at 22' to form the cam faces which are engaged by the sliding member 24' mounted on the outside of the casing in a manner similar to that shown in the first modification. Contact element 18' is provided with a push button 21' extending through an aperture in the casing of the hand lamp. The contact elements are attached to the casing by a rivet 20' which passes through their common end.

The operation of this modification of the invention is substantially the same as in the case of the first modification. If it be desired to light the lamp intermittently button 21' is depressed to establish the lamp circuit, which will be maintained as long as the element 18' is held in contact with the terminal 17' of the battery. When element 18' is actuated element 19' may or may not be depressed, depending, among other factors, upon the length of the cuts between the elements, the relative resiliency of the elements, and their relation to the common end which is not cut. When it is desired to cause a

permanent lighting of the lamp the sliding member 24' is slipped along until it engages and depresses contact element 19' into engagement with battery terminal 17'. Contact element 18' may or may not engage the battery terminal 17' depending upon the factors mentioned above.

While the invention has been shown embodied in one particular construction it will be understood that various changes may be made therein without departing from the principle of the invention.

I claim:

1. Contact mechanism for a battery hand lamp comprising, in combination, a conductor, a contact element adapted to be swung into engagement with said conductor, a second contact element adapted to be swung by said first named element and into engagement with the conductor, and means for actuating the second contact element and retaining it in place against the conductor.

2. Contact mechanism for a battery hand lamp, comprising, in combination, a conductor, a contact element adapted to be swung into engagement with said conductor, a second contact element adapted to be swung by said first named element and into engagement with said conductor, and means for actuating said second contact element independently of the first contact member and retaining it in place against the conductor.

3. A switch for battery hand lamps comprising, in combination, a pair of spring-contact elements, means associated with one of said elements whereby both of said elements may be actuated simultaneously, and means associated with the other of said elements whereby it may be actuated independently of said first-named element.

4. A switch for battery hand lamps, comprising a pair of spring-contact elements, means associated with one of said elements whereby both of said elements may be actuated together, and means associated with the other of said elements whereby it may be actuated independently of said first-named element and retained in circuit-closing position.

5. A switch for battery hand lamps comprising a plurality of spring-contact elements adapted to engage the terminal of a battery, a cam formed in one of said elements, sliding means adapted to co-operate with said cam to retain said element in circuit-closing position, and means associated with the other element for actuating both elements.

6. A switch for battery hand lamps comprising a plurality of spring-contact fingers attached to the casing of the hand lamp and adapted to engage a terminal of a battery within said casing, means associated with one of said fingers and extending through an aperture in the other of said fingers and

through the casing whereby the one finger may be actuated independently of the other finger, and means associated with said other finger and extending through the casing 5 whereby both fingers may be actuated.

7. In a battery hand lamp, a switch for establishing a circuit between the battery and the lamp comprising a plurality of spring-contact fingers attached to the casing 10 of said hand lamp, one of the fingers

having a push-button extending through the casing for actuating both fingers and also having an aperture through which a bent portion of the other finger extends, and a sliding member mounted on the casing and 15 adapted to engage the said bent portion to actuate the second contact finger independently of the first contact finger.

In testimony whereof I affix my signature.
ERNEST ALSCHULER.
